UNITED STATES PATENT OFFICE

172,655

PORTABLE SAWMILL

Alvin Woodruff, Dallas, Oreg.

Application December 29, 1952, Serial No. 22,901

Term of patent 14 years

(Cl. D93—3)

To all whom it may concern:

Be it known that I, Alvin Woodruff, a citizen of the United States and a resident of Dallas, county of Polk, and State of Oregon, have invented a new, original, and ornamental Design for a Portable Sawmill, of which the following is a specification, reference being had to the accompanying drawing, forming part hereof.

Fig. 1 is a front elevational view of a portable sawmill showing my new design;

Fig. 2 is a side elevational view; and

Fig. 3 is a rear perspective view thereof.

I claim:

The ornamental design for a portable sawmill, substantially as shown.
